UNITED STATES PATENT OFFICE.

WILLIS E. TITUS, OF HANOVER, MICHIGAN.

FLY-KILLER.

1,143,738.

Specification of Letters Patent. Patented June 22, 1915.

Application filed August 20, 1914. Serial No. 857,742.

To all whom it may concern:

Be it known that I, WILLIS E. TITUS, citizen of the United States, residing at Hanover, in the county of Jackson and State of Michigan, have invented certain new and useful Improvements in Fly-Killers, of which the following is a specification.

This invention relates to that class of devices commonly known as fly killers and more particularly to an improved receptacle adapted to contain a poisonous liquid and so constructed that flies may gain access to the said liquid, the invention having as its primary object to provide a receptacle which may be readily attached to the wire fabric of a screen door in such position that flies alighting upon the door will be attracted by the presence of the said liquid to feed thereon.

20 A further object of the invention is to provide an improved device of this character so constructed that when operatively attached to the fabric of a screen door, flies alighting upon either side of the fabric of the door may gain access to the wicks carried by the receptacle, which wicks being saturated with the poisonous liquid, will permit the flies to feed thereon.

The invention has as a still further object 30 to provide an improved device of this character which, while being especially adapted for attachment to screen doors, will also be adapted to rest upon any other suitable form of support in such position that the wicks carried thereby will be held uppermost to thus prevent the spilling of the liquid contained within the receptacle, and further so constructed that the said device may be easily suspended by a cord or other flexible 40 element from a nail or other suitable form of support. And the invention has as a still further object to generally improve the construction and increase the efficiency of devices of the above described character.

45 With these and other objects in view, my invention will be more fully described illustrated in the accompanying drawings and then specifically pointed out in the claims which are attached to and form a part of 50 this application.

In the accompanying drawings: Figure 1 is a perspective view showing my improved device attached to a screen door, the door being conventionally shown. Fig. 2 is a 55 fragmentary perspective view particularly illustrating the formation of the receptacle

at one end thereof, Fig. 3 is a transverse sectional view particularly illustrating the disposition of the wicks carried by the receptacle, Fig. 4 is an end view of the device 60 showing the disposition of the hooks or hangers carried thereby and illustrating the manner in which the receptacle is disposed to rest upon a support, and Fig. 5 is a perspective view showing the device suspended 65 by a cord.

Corresponding and like parts are referred to in the following description and indicated in all the views of the drawings by the same reference characters.

Referring more particularly to the drawings, my improved device includes a receptacle 10 which may of course, be constructed any desired size of length and which may be formed of any suitable material. However, 70 the receptacle 10 is preferably constructed of suitable sheet metal and is substantially semi-circular in cross-section, being provided with the convex or continuously curved portion 11 which is joined at its longitudinal edges by the flat side wall 12, the said receptacle being closed at its extremities by suitable end walls 13 and 14. Upon one side of the receptacle, the adjacent margin of the side wall 12 is extended laterally and the adjacent margin of the wall 11 is folded over said laterally extending portion to provide an upstanding flange 14'. 75

As best shown in Fig. 2 of the drawings, the sides of the receptacle are extended longitudinally beyond the end wall 14 to form a terminal flange 15 and the said end wall 14 is provided with a suitable opening disposed to receive a cork or other closure 16'. By this construction, a suitable poisonous liquid 80 may be easily introduced within the receptacle by simply holding the receptacle in a vertical position and pouring the said liquid into the pocket formed by the flange 15, when it will flow through the opening 85 formed in the end wall 14 into the receptacle. 90

Formed in one longitudinal edge of the receptacle at the intersection of the side wall 12 and the curved side wall 11 thereof and 105 in the flange 14' are a series of longitudinally spaced openings 16, the said openings as best shown in Fig. 3 of the drawings being relatively wide transversely to extend into the upper margin of the side wall 12 and to 110 also extend transversely of the side wall 11. Arranged within the said openings and de-

pending well within the receptacle, are a plurality of wicks 17. Each of the wicks 17 is preferably folded upon itself and so arranged that the extremities thereof will 5 project out through the adjacent opening 16 as clearly illustrated in the drawings, although it is to be understood that this particular arrangement is not absolutely essential. However, the particular purpose there- 10 of will presently appear.

The wicks 17 may be formed of any suitable material and are disposed to be immersed at their inner extremities within the liquid contained within the receptacle, so 15 that by capillary action, the outer exposed extremities of the said wicks will be constantly saturated with the liquid. In this connection, it may be stated that it is intended that the receptacle shall be filled with 20 some suitable poisonous liquid which shall be sweetened so that the presence of the liquid upon the wicks 17 will attract flies to the said wicks to feed upon the liquid. It will be noted that the outer extremities of 25 the wicks 17 will be normally disposed substantially in alinement with the flange 14' and the said flange will therefore, provide a protection for the free ends of the wicks.

Arranged upon the receptacle 10 adjacent 30 the extremities thereof are hooks or hangers 18. The said hooks are each preferably formed from a length of suitable resilient wire which, adjacent one end, is secured to the side wall 11 in any suitable 35 manner, the contiguous extremity of the wire being extended in spaced relation to said wall 11 upon one side thereof, and being thence turned inwardly to form a foot 18', the adjacent extremity of the wire being 40 secured to the side wall 11 upon the lower side thereof. It will be noted that the said hooks are arranged transversely of the body portion of the receptacle 10 and at the flange 14', the length of wire forming each of said 45 hooks is again bent upwardly to provide a spring loop 19, and is thence continued at its free extremity in substantial parallel relation to the side wall 12 to form a bill 20, the free extremities of said hooks normally bearing 50 resiliently against the side wall 12. As shown in Fig. 1 of the drawings, the receptacle 10 may thus be suspended or swing- 55 ingly mounted upon the wire fabric of a screen door by the hooks 18 with the flat side wall 12 of the receptacle resting against the said wire fabric, the free extremities of the said hooks being inserted through the mesh of the screen.

It is to be noted that the free extremities 60 of the hooks 18 or the bills thereof, extend throughout the major portion of the width of the side wall 12 toward the base of the receptacle so that the resilient action of the said free extremities of the hooks will serve 65 to hold the receptacle clamped against the

wire fabric of the screen door to thus prevent movement or flapping of the receptacle when the door is opened and closed. The door shown in Fig. 1 of the drawings is of conventional construction and has been illustrated for convenience. Particular attention is now called to the fact that when the receptacle 10 is thus attached to a screen door or other wire fabric, one extremity of each of the wicks 17 adjacent the said fabric 75 will, under normal conditions, project through the interstices of the fabric so that flies upon one side of the screen may easily gain access thereto while the opposite extremity of each of said wicks will normally 80 rest upon the opposite side of the fabric so that flies upon the opposite side of the screen may feed upon the liquid, from that extremity of each of said wicks. This is obviously a feature of advantage and is made 85 possible by the peculiar disposition of the opening 16 within the upper edge of the receptacle 10 as well as the particular arrangement of the wicks 17, above set forth. While the device is thus especially adapted 90 for attachment to the wire fabric of a screen door or any other ordinary window screen, still, as shown in Fig. 5 of the drawings, it will be observed that the receptacle may be readily suspended by a cord or other flexible element from a nail or other form of support by tying terminal knots in the cord and inserting the said knots through the loops 19, the cord shown in this figure being indicated at 21. Thus, the loops 19 perform 100 a dual function in that they serve to resiliently actuate the free extremities of the hooks 18 and also provide a convenient means whereby the receptacle may be suspended as just above set forth. In the event 105 it is desired to position the receptacle upon a window sill, table, or other flat support, it will be noted that the portions 18' provided by the hooks 18 are disposed to contact with the support to maintain the wicks in a relatively upright position, as shown in Fig. 4 of the drawings. Obviously, I provide a very simple and convenient means for effecting this result and it will thus be noted 110 that the receptacle may be arranged in various places within a house as desire may demand. It will therefore be seen that I provide a very simple and efficient construction for the purpose set forth wherein the receptacle may be readily attached to the 115 fabric of a screen door or other wire fabric, and when so positioned upon the door, will be held firmly thereon. It will further be seen that I provide an arrangement of wicks whereby when the receptacle is attached to 120 the wire fabric, flies may gain access to the wicks from each side of the fabric, and that while the invention is particularly adapted to be attached to screening, it may, with equal facility, be supported by a flexible ele- 125

ment which may be readily attached to or detached from the receptacle, and that the receptacle is also so constructed that when positioned upon a flat surface, the wicks carried by the receptacle will be held in a relatively upright position, to prevent spilling of the liquid contained within the receptacle.

Having thus described my invention, 10 what I claim and desire to secure by Letters Patent, is:—

1. A device of the character described including a receptacle having a flat side and provided with an opening, the said receptacle being adapted to contain a liquid, a wick arranged in said opening and disposed to contact with the liquid, and a suspending hook having its free extremity arranged parallel with the flat side of the support and 20 extending throughout the major portion of the transverse width thereof, said receptacle being adapted to be suspended upon a support with the free extremity of the hook extending through the support to contact with 25 the side thereof opposite the receptacle for urging the receptacle toward the support.

2. A device of the character described including a receptacle having one curved side, and one flat side intersecting the curved side, 30 and provided with an opening, the said receptacle being adapted to contain a liquid, a wick arranged within said opening and disposed to contact with the liquid, and a suspending hook carried by the receptacle, 35 the said hook being formed from a length of suitable resilient wire having one extremity thereof secured to the curved side of the receptacle to extend transversely thereof, the said wire being bent at one of 40 the intersections of said sides to extend upwardly upon one side thereof to provide a suspending loop and being thence continued to form a bill normally abutting the flat side of the receptacle.

45 3. A device of the character described including a receptacle adapted to contain a liquid and having a laterally extending flange formed thereon, the said receptacle being provided with an opening at the base

of said flange, and a wick arranged in said opening and disposed to contact with the liquid, said flange forming a protection for the wick at its outer extremity.

4. A device of the character described including a receptacle having a curved wall 55 and adapted to contain a liquid, said receptacle having an opening formed therein, a wick arranged in said opening and disposed to contact with the liquid, and a supporting hook carried by the receptacle, the said hook 60 providing a foot adjacent the curved wall of the receptacle disposed to contact with a support to maintain the wick in a relatively upright position.

5. A device of the character described including a receptacle adapted to contain a liquid and having a laterally extending flange formed thereon, the said flange being provided with a notch and said receptacle having an opening formed therein at the inner extremity of said notch, and a wick arranged in said opening and disposed to contact with the liquid, the free extremity of the wick being disposed in said notch of the flange.

6. The combination with a swinging support having a reticulate portion, of a receptacle carried thereby and adapted to contain a liquid, the receptacle being provided with an opening, a wick arranged in said opening and disposed to contact with the liquid, the free extremity of the wick being adapted to normally rest against the reticulate portion of the support, and suspending means freely connecting the receptacle with the support and extending through the reticulate portion thereof, the said means being adapted to coact with the support for urging the receptacle laterally toward the support to normally seat thereagainst with the said 90 wick bearing at its free extremity, against the said reticulate of the support.

In testimony whereof I affix my signature in presence of two witnesses.
